UNITED STATES PATENT OFFICE.

EDWIN L. GILES, OF LOWELL, MASSACHUSETTS, ASSIGNOR TO THE LAMSON CASH RAILWAY COMPANY, OF SAME PLACE.

SWITCH FOR STORE-SERVICE APPARATUS.

SPECIFICATION forming part of Letters Patent No. 310,815, dated January 13, 1885.

Application filed May 24, 1884. (No model.)

To all whom it may concern:

Be it known that I, EDWIN L. GILES, a citizen of the United States, residing at Lowell, in the county of Middlesex and State of Massachusetts, have invented certain new and useful Improvements in Switches for Store-Service Apparatus, of which the following is a specification.

My invention relates to that class of store-service apparatus in which the ways consist of parallel rails; and my invention consists in a switch constructed and combined with the rails of the track, as fully set forth hereinafter, so as to prevent the discharge of any carriers but those intended to be deflected by the switch, and so as to reduce the space heretofore required for switch appliances.

In the drawings, Figure 1 is a longitudinal section of sufficient of the track of a store-service apparatus to illustrate my invention. Fig. 2 is a plan view, and Fig. 3 is a cross-section on the line 1 2, Fig. 1.

It has heretofore been common in providing store-service apparatus with what are called "drop-switches" to make the switch from a portion of the track pivotally secured, so that it will tilt under the weight of the ball and direct the latter to the desired receptacle. In such cases the switch-sections of the track 30 have been either pivoted about midway between their length or nearer the end adjacent to the highest portion of the track, the switch-section in either case dropping below the track, and serving as a guide to direct the carriers to the receptacle.

In those cases where the switch-sections have been centrally pivoted, one portion, when the switch is tilted, projects above the track and the other portion extends below, and in either 40 case the switch occupies an extended portion of the track, and the space or opening left in the track when the switch is tilted is extensive, and frequently permits the passage of carriers from the track at points where they 45 should not be delivered. To obviate these objections I cut away the rails *a a* of the main track for a distance but little longer than the diameter of the carrier which is to pass through the track at this point, and to these cut-away 50 portions I adapt the rails *b* of the switch-section *B*, and pivot said section at the extreme

ends of the rails nearest the lowest portion of the track, so that when the switch-section is tilted to the position shown in Fig. 1 the track will not be opened on the lowest side of the 55 switch, while the opening on the opposite side will be but little more than sufficient for the passage of the carrier, the result being that the latter is quickly delivered from the track to the receptacle, and the switch portion, closing 60 instantly, affords a continuous track for the passage of the following carriers.

The switch may be opened and closed by any of the usual or available appliances. For instance, it may be locked in a horizontal position by means of a latch, *D*, pivoted beneath the track, and engaging with a lip, *e*, upon the switch-section, a lever, *I*, overhanging the track and connected to the latch, being struck by the carriers which are to be delivered at 70 such point, and thus withdrawing the latch, so that the track-section can be raised by a counter-weight, *W*, or any other suitable means.

As a means of closing the switch, I provide 75 the switch-section *B* at the under side with an arm, *J*, constructed and arranged to occupy a position below the opening in the track when the switch-section is elevated, so that the carrier which passes to said opening must 80 strike said arm, and by its contact therewith carry the switch-section to a horizontal position, in which it will be locked by the latch *D*.

Where the switch-section is pivoted centrally, so that there is an opening at the lowest portion of the track beyond the pivot-point, when a carrier is upon the switch at the time it is opened by a following carrier both will be discharged into the receptacle, although the first is intended for a more distant station.

It will be seen that the device above described is not open to this objection, inasmuch as the carrier upon the switch-section *B* at the moment the latter is opened by a following carrier is directed from the switch onto the main track and there continues.

By the above-described construction I am enabled to reduce the length of the switch-section to a minimum, and can also place the 95 unlocking device in close proximity to the pivot-point, so that the space actually occu-

pied upon the track by the switch and its appurtenances is very much less than in appliances heretofore employed.

When this switch is used in connection with 5 a supplemental section, A', intended to retain the carriers until they pass to a drop-basket or other receptacle, the arm J serves as a guard to prevent the carrier from passing beyond the end of the receptacle, and also lessens the 10 force with which the carrier passes to the supplemental track.

The improved switch above described will 15 be found specially serviceable in stores where a large business is conducted and carriers of different sizes follow each other in close succession, inasmuch as one of contiguous carriers can open the switch and pass downward and then close the switch before the following 20 carrier reaches the position adjacent to the end of the switch.

Without limiting myself to the precise construction and arrangement of parts shown, I claim—

1. A switch for store-service apparatus, in 25 which a switch-section of the track adjacent

to each station is pivoted close to its end adjacent to the lower portion of the track, and is combined with a locking and releasing device adapted to be operated only by the carriers to be discharged at such station, and with 30 an arm arranged to be struck by the carriers for moving the switch to a horizontal position as a carrier passes through the track, substantially as described.

2. The combination of the switch-section 35 pivoted at its lower end to the main track, locking device adapted to be operated by the carriers, arm on the switch-section arranged to be struck by the carriers as they pass from the track, and a supplemental track arranged 40 below the main track, substantially as set forth.

In testimony whereof I have signed my name to this specification in the presence of two subscribing witnesses.

EDWIN L. GILES.
